H. KARL.

ELECTRIC SWITCH CONTROLLED BY RAILROAD ROLLING STOCK.
APPLICATION FILED SEPT. 21, 1915.

1,329,773.

Patented Feb. 3, 1920.

UNITED STATES PATENT OFFICE.

HEINRICH KARL, OF NEW YORK, N. Y.

ELECTRIC SWITCH CONTROLLED BY RAILROAD ROLLING-STOCK.

1,329,773.

Specification of Letters Patent.

Patented Feb. 3, 1920.

Application filed September 21, 1915. Serial No. 51,777.

To all whom it may concern:

Be it known that I, HEINRICH KARL, a citizen of Germany, and resident of the borough of Manhattan, city, county, and State of 5 New York, have invented certain new and useful Improvements in Electric Switches Controlled by Railroad Rolling-Stock, of which the following is a specification.

My invention relates to a circuit-controlling apparatus adapted to be operated by a train, car, or engine moving on a railroad, to 10 actuate various devices (for instance as signals), and the arrangement may be such that the circuit is normally open, or normally 15 closed, or when a plurality of circuits are controlled at the same time, some of them may be normally open and others normally closed.

Two examples of my invention are illustrated in the accompanying drawings, in 20 which, Figures 1 and 2 are diagrammatic vertical sections showing one form of my apparatus, in the normal or inactive and in the operated or active position respectively; 25 Fig. 3 is a diagrammatic plan view, with parts in section; and Fig. 4 is a longitudinal elevation of another form of my invention, with parts in section.

In Figs. 1, 2 and 4, I have indicated at 30 10, the wheel of a railroad engine or car, arranged to run on a track rail 12, said wheel constituting the actuating member, carried by the railroad rolling stock, for operating the improved controller or switch apparatus, 35 located at a suitable point of the track.

According to Figs. 1 and 2 the actuating member 10 is adapted to engage and depress a curved spring, the normal position of 40 which is indicated by full lines in Fig. 1, and by dotted lines in Fig. 2. This spring bears on, and is adapted to push downward when depressed, a plunger 14 suitably guided for up and down movement in a stationary frame 13. To the lower end of the plunger 45 is attached pivotally one end of a connecting rod 15, the other end of which has a similar connection with a disk 20 mounted to turn on a rod or axle 18. To the disk 20 is secured rigidly a switch member 19, provided 50 at its periphery with spaced insulated portions, the relative arrangement of which corresponds to that of stationary contacts or brushes 22, 23 and 23^a respectively. In the

position shown in Fig. 1 the brushes engage the insulated portions, and the circuits are 55 broken; in Fig. 2, the three brushes engage the conducting portion of the switch member 19, and the circuits are closed. The disk 20 and switch member 19 are under the influence of mechanism, such as the weight 31 60 connected to the disk by a rope or chain 32, tending to bring the parts to the normal position shown in Fig. 1. In this position, the weight 31 may rest on the bottom of the casing 21, which incloses and protects the 65 switch apparatus.

The disk 20 is provided with a shoulder 24, and when the depression of the spring 11 gives a partial rotation to said disk, bringing it to the position Fig. 2, the shoulder 24 70 will clear the head 28 of a sliding rod 27, supported and movable in holes of brackets 21^a within the casing 21. A spring 26 tends to move said rod toward the center or axis 18 of the disk. The head 28 will therefore 75 be projected into the locking position, to prevent the return of the switch member 19 to its normal position until the head 28 is retracted as explained hereinafter, when the weight 31, which has been raised by the turning of the disk 20, will restore the switch member to the normal position (Fig. 1). The engagement between the spring or actuated member 11 and the plunger 14 is preferably a loose one, so that said spring may 80 return to its normal position as soon as the wheel 10 clears the spring 11.

The circuits closed by the engagement of the contacts 22, 23, and 23^a with the conducting portion of the switch member 19, may 90 control any device or devices susceptible of electric control, and examples of electrical operation of various devices by passing trains are well-known in the art. As an example, I have shown the contact 23^a connected by a wire 16 with a bell 17 (this being an instance of an acoustic signal), while the contact 23 is connected by a wire 35 with an electromagnet coil 36 controlling, say, a semaphore signal 37, see Fig. 3, (this being an 100 instance of an optical signal). Current may be supplied in any suitable manner, as by means of a generator 33 from which a wire 34 leads to the contact 22.

In order to retract the head 28 from its 105 locking position, I have shown an armature

29 on the end of the rod 27 opposite to the head 28, said armature being adapted to be attracted by an electromagnet 30. This magnet may be energized at the proper time 5 in any well-known or approved manner. For instance, when the train has proceeded to the desired distance (say, a block) after the switch member 19 has been turned by the 10 train may (by means well-known in the art) send the current from a source of electricity through a circuit including the coil of the electromagnet 30, a wire 38, a rail portion or ramp 39, and a track rail 25, the circuit 15 being normally interrupted between said ramp and said track rail and closed in a well-known manner as a train passes this point.

In Fig. 4, I have illustrated an embodiment of my invention in which two apparatus 20 of the character described above are located at the same point of the track and connected in the manner to be set forth presently. The parts designated by the numerals 19', 20', 21', 22', 23', 25', 29', 30', 31', 25 33', 34', 35', 36', 37', 38' and 39' are substantially the same as those bearing similar numerals in Figs. 1, 2 and 3, but the switch member 19' is shown with only two insulated portions on its periphery, and there are two 30 contacts 22', 23' instead of the three contacts 22, 23, 23a. Thus a single circuit (33', 34', 23' 19', 22', 35', 36') is closed when the disk 20' is turned to bring both contacts 22', 23' in engagement with the conducting portion 35 of the switch member 19'. Of course the circuit arrangement of Figs. 1 and 2 might be employed in Fig. 4, and vice-versa.

The double device of Fig. 4 is intended to have one of its halves or sections operated 40 only by trains traveling in the one direction, and the other section only by trains traveling in the opposite direction. This form 45 of my invention is designed for single-track lines.

45 The two halves or sections of the apparatus shown in Fig. 4 being similar, only one of them has been illustrated in detail, and its description will suffice.

The first wheel 10 of a train traveling toward the left will engage the roller 40 on a 50 spring or actuated member 41, which is thus also moved toward the left as indicated by dotted lines, causing the levers 42, 42' which are pivotally connected with said member 41, to rock on their fulcrum pins 43, 43' respectively. The lower ends of these levers therefore swing to the right, and the wire, rope, or chain 45 will transmit the motion of the lever 42 to the left-hand section of the 55 apparatus, owing to the pull exerted on said flexible connection 45. The switch member 19' on the left will therefore be turned (and latched as described above) to operate the signal 37' or other controlled device, by closing 60 the circuit between the contacts 22', 23' 65

and the conducting portion of the switch member 19'. The lever 42' however, in this case will not operate the right-hand section of the apparatus, since movement of the lower end of said lever 42' will simply cause 70 the flexible connection 45' to sag or become slack, as indicated by dotted lines.

When a train travels toward the right, its first wheel will engage the roller 40' at the 75 left-hand end of the spring 41, move it toward the right, and swing the levers 42, 42' so that their lower ends will move toward the left, pulling on the connection 45' to operate the right-hand part or section of the apparatus, while the connection 45 will become slack so that the left-hand section of the apparatus will not be affected.

The right-hand section of the apparatus will therefore, be operated only by trains or 80 rolling stock moving toward the right, and the left-hand section only, by rolling stock moving toward the left.

When a train passes to a succeeding block to the right or left, the solenoid 30' at the 85 left or right as the case may be releases its latch 27' on the slide rod 28' and the parts 40, 40', 41, 42 and 42' will be restored to normal position under the action of the weight 31'.

While I have shown satisfactory and preferred embodiments of my invention, it is 90 obvious that changes may be made therein within the spirit and scope thereof, as defined in the appended claims.

I claim:

1. In apparatus of the class described, a 100 movable member arranged adjacent to a railroad track and adapted to be actuated by passing trains, an electric switch mounted to rock and arranged to be operated by said member mechanically, a disk connected with said switch and provided with a shoulder, latching means adapted for engagement with said shoulder, and a device for moving said latching means to the releasing position.

2. In apparatus of the class described, a 105 movable member arranged adjacent to a railroad track and adapted to be actuated by passing trains, an electric switch mounted to rock and arranged to be operated by said member mechanically, a disk connected with said switch and provided with a shoulder, latching means adapted for engagement with said shoulder, and an electric device 110 controlled by passing trains for moving said latching means to the releasing position.

3. In apparatus of the class described, a 115 member arranged adjacent to a railroad track and adapted to be moved lengthwise of such track by passing trains, in one direction or the other, according to the direction in which the actuating train travels, two electric switches, and mechanical connections between said member and said 120

switches, each of said connections including an element for transmitting motion in one direction only, and becoming slack upon the movement of said member in the other direction, one of said elements being operative to transmit motion to the respective switch when the said member moves in one direc-

tion, and the other element being operative to transmit motion to the other switch when said member moves in the other direction. 10

In testimony whereof I have hereunto set my hand.

HEINRICH KARL.
